UNITED STATES PATENT OFFICE.

HERMAN DOERING, OF REEDSBURG, WISCONSIN.

NECK-YOKE.

SPECIFICATION forming part of Letters Patent No. 654,958, dated July 31, 1900.

Application filed May 4, 1900. Serial No. 15,536. (No model.)

To all whom it may concern:

Be it known that I, HERMAN DOERING, a citizen of the United States, and a resident of Reedsburg, county of Sauk, State of Wisconsin, have invented certain new and useful Improvements in Neck-Yokes, of which the following is a specification, reference being had therein to the accompanying drawings, in which—

10 Figure 1 is a plan view of a neck-yoke provided with my improvements; Fig. 2, an enlarged plan view of one end of the neck-yoke; Fig. 3, a transverse section through the collar-strap-holding ring, and Figs. 4 and 5 detail 15 plan views showing other ways of connecting the ring to the end of the neck-yoke bar.

The object of the invention is to provide an extremely simple, inexpensive, and durable device for attaching the collar-straps to the 20 respective ends of the neck-yoke bar in such manner that the straps shall have a free swinging movement from side to side, so that twisting and wear of the straps is avoided, whereby the straps will wear as long as the 25 other parts of the harness, as more fully hereinafter set forth.

Referring to the drawings by reference-letters, *a* is a closed ring or eye secured rigidly to the end of the neck-yoke bar by means 30 of a ferrule *b*, with which it is formed integral, as shown in Fig. 2, or by any other suitable means—as, for instance, by means of a concaved plate fitted against the front side of the neck-yoke bar and suitable rivets or 35 bolts extending through the bar, as shown in Fig. 4, or by means of a tongue *d* fitted in a hole in the end of the neck-yoke and secured therein by a transverse rivet or bolt, as shown in Fig. 5, a ferrule *e* being fitted on the end 40 of the bar, as usual. The ring or eye has its inner face formed into an annular flange *f*, having its upper and lower faces beveled inward to form oppositely-facing inclined seats, the flange being substantially V-shaped in 45 cross-section. Seated against each of the beveled faces of the flange is a disk *g*, whose edge is beveled correspondingly to the adjacent face of the flange and whose outer face

is flush with the surface edge of the ring. The inner faces of these disks abut against each other and are rigidly clamped together by rivets or screws *h* passing through the disks, whereby the two disks form a sort of turn-button which is free to rotate within the ring. The two disks are provided with registering slots *i*, extending across their centers, but terminating short of their edges, so that the slots are closed on all sides. Into these slots the collar-straps are passed, and while in use the disks turn on the ring as the straps 60 are swung from side to side, as is evident.

It will be observed that this device avoids twisting and straining the straps and also avoids the wear that occurs where the connecting eyes or hooks are rigid.

It is essential, as will be observed, that the plates composing the rotating button be separable, so that they may be secured in the ring or eye without bending or cutting the same.

Having thus fully described my invention, 70 what I claim, and desire to secure by Letters Patent, is—

A collar-strap-fastening device for neck-yokes, consisting of a ring provided with means for fastening it to a neck-yoke bar and 75 having an inward-extending flange formed on its inner face, this flange having oppositely-facing inclined sides extending continuously around the ring, and a pair of disks fitted into the opposite sides of the ring and 80 beveled at their edges to correspond with the inclined seats in the ring, these beveled edges being continuous and unbroken and the adjacent faces of the disks abutting against each other, said disks being provided with closed 85 registering strap-slots, terminating short of the edges of the disk, and means for rigidly fastening the disks together.

In testimony whereof I hereunto affix my signature, in the presence of two witnesses, 90 this 20th day of January, 1900.

HERMAN DOERING.
